CONTAINER FEEDING MECHANISM FOR
CAPPING MACHINES

Edward M. Fore, Zolfo Springs, Fla., assignor of
fifty per cent to Joseph A. Mancini, Wauchula,
Fla.

Application July 27, 1948, Serial No. 40,834

6 Claims. (Cl. 226—88.1)

1

This invention relates to container capping machines of the type disclosed in U. S. Patent No. 1,841,051 granted January 12, 1932, to Abraham Podel, and has more particular reference to a container feeding mechanism for machines of that type.

An object of the invention is to provide a feeding mechanism whereby the containers may be placed underneath the capping head and on the container support which presents the container to the capping head, which feeding mechanism is so timed as to place the container in and remove the same from capping position while the container support is lowered.

Another object of the invention is to provide a feeding mechanism which may be readily applied to existing capping machines, and which is comparatively simple in construction and highly efficient in operation.

The exact nature of the present invention, as well as other objects and features thereof, will become apparent from the following description when considered in connection with the accompanying drawings, in which:

Figure 1 is a view partly in side elevation and partly in section, of a container capping machine equipped with a container feeder mechanism embodying the present invention;

Figure 2 is a front elevational view thereof, partly broken away;

Figure 3 is a view similar to Figure 1 with other parts in section and parts removed;

Figure 4 is an enlarged fragmentary top plan view of the container carrier and the conveyor forming part of the feeding mechanism;

Figure 5 is a fragmentary vertical section taken on line 5—5 of Figure 4;

Figure 6 is a fragmentary horizontal section taken on line 6—6 of Figure 5;

Figure 7 is a fragmentary vertical section taken on line 7—7 of Figure 4, with the containers part raised;

Figure 8 is a front elevational view, partly broken away, of the construction shown in Figure 4;

Figure 9 is a horizontal section taken on line 9—9 of Figure 8;

Figure 10 is a horizontal section taken on line 10—10 of Figure 5.

Referring in detail to the drawings, the present container feeding mechanism is shown applied to a capping machine including a column 5 having a base 6 provided with a rear framework 7 for supporting driving mechanism. The driving mechanism includes a gear 8 secured on a

2

shaft 9 which is journaled in a bearing 10 of framework 7. Shaft 9 drives a further shaft 11 through gears 12 and 13, said shaft 11 being journaled in a further bearing 14 of framework 7. A motor 15 is mounted on framework 7 and has a power shaft provided with a pinion 16 which meshes with gear 8. The gear 13 is connected to the shaft 11 through a clutch 17 which, when in the position shown in Figure 3, prevents the gear 13 from being effective upon the shaft 11. A lever 18 is pivoted at one end and operatively connected to the clutch member to pull it downwardly out of position to effect the capping operation when said lever 18 is pressed downwardly in opposition to a spring 19 (Figure 1). Ordinarily, the capping machine is provided with a treadle in place of the lever 18. However, such treadle is replaced by the lever 18 and the latter is secured upon a shaft 20 journaled in the base 6 and having a projecting end upon which a further lever 21 is secured. The spring 19 is connected to lever 21, and said lever 21 is operatively associated with the present container feeding mechanism in a manner which will later become apparent. It will be understood that the clutch 17 is in effective position to connect the driving mechanism with the shaft 11 only when the lever 18 is depressed. In order to prevent the machine from running under its own momentum, a brake band 22 is secured about a collar 23 on the shaft 11, and is held in position by members 24. A table mechanism is provided for supporting and raising the containers, which mechanism comprises a rod 25 mounted in bearings 26, with its lower end threaded into a sleeve 27 which has a cam roller 28 attached thereto in engagement with a suitable groove 29 in a cam 30 to positively move a jar support 31 both upwardly and downwardly. The support 31 is adapted to pass through a suitable opening in a stationary table 32, and its upper surface is flush with the table when in lowered position. It will be understood that when the lever 18 is operated, the cam 30 raises the support 31 and the container thereon so that said container is presented to a sealing head 32. This sealing head is shown as of the type disclosed in U. S. Patent No. 2,154,409 issued April 11, 1939, to Abraham Podel. The capping or sealing head 32 comprises an upper die against which the closure cap on the container is pressed when the container is raised to capping or sealing position and a lower die formed with segmental jaws. The segmental jaws of the lower die are attached to the lower ends of vertical rods 34 which are connected by members 35 to a pin

36. A lever 37, pivoted by means of a pin 38, is adapted to raise and lower the rods 34 to operate the segmental jaws of the lower die as clearly disclosed in the last mentioned patent. The mechanism for operating the segmental jaws comprises a rod 39 extending through the column 5 with a cam roller 40 at the lower end thereof riding upon a cam 41. The cam roller 40 is held resiliently against the cam by a spring 42 which raises and closes the lower die by pressing downwardly the rod 39 when the dwell in the cam reaches the cam roller 40. As the jaws move upwardly, they are pressed inwardly in opposition to springs to engage the bead in the skirt of a closure cap and to press said closure cap against the upper die to force the closure cap gasket against the container in a manner well known in the art and clearly set forth in the prior patents referred to above.

The principal object of the present invention is to provide means for feeding containers 43, one at a time, beneath the capping or sealing head 33 and on the support 31 so that said container will be presented to the capping head 33 for being capped when the support 31 is raised, and for subsequently removing the capped container from the support 31. This feeding means includes a guiding flange 44 provided on the table 32 partially surrounding a rotatable container carrier 45 by means of which the containers are slid on the table 32 to capping position upon the support 31. The carrier 45 is mounted to turn about a vertical axis defined by shaft 46, and it is formed with a plurality of segmental pockets 47 which are adapted to receive the containers and to move the same along the table 32. The carrier 45 overlies the upper run of the endless belt 48 of a suitably driven conveyor, which upper run of belt 48 travels in a recess of table 32 directly in front of the container support 31. Carrier 45 has a hub 49 formed with ratchet teeth 50 which correspond in number and position to the pockets 47. Journaled on shaft 46 above the hub 49 is a plate 51 that carries a spring pressed pawl 52' yieldingly engaged with the portion of hub 49 provided with teeth 50. An operating rod 53 is pivoted at its rear end to the plate 51, and the arrangement is such that when the rod 52 is moved rearwardly pawl 52' engages a tooth 50 so as to partially rotate carrier 45 for moving a container from conveyor belt 48 onto the container support 31, whereupon the support 31 may be raised to present the container to the capping head 33 as shown in Figure 7. The rod 52 is then moved forwardly so as to reset the pawl 52' relative to the next tooth 50, whereby a succeeding container may be transferred from conveyor belt 48 to container support 31 when the latter is lowered, and whereby the previously capped container may be transferred from said container support 31 back to the conveyor belt 48 at the opposite side of carrier 45. Belt 48 may then remove the capped container from the carrier 45 when traveling in the direction of the arrows shown in Figure 4.

Attached to the under side of table 32 are spaced brackets 53 on which is journaled a rock shaft 54. Secured on rock shaft 54 is an upwardly projecting lever 55 to which the forward end of rod 52 is pivoted as at 56. Another lever 57 is secured on rock shaft 54 and projects rearwardly from the latter through a vertical slotted plate 58 carried by a collar 59 mounted on rod 25 for movement with the latter. The arrangement is such that when rod 25 is raised to elevate the

5 container and present it to the capping head 33, lever 57 is swung upwardly so as to move lever 55 forwardly and to thereby set pawl 52' for the next actuation of carrier 45 through the medium of rod 52 and plate 51 and by engagement with a tooth 50. Due to the slot in plate 58, the rod 25 may return to lowered position without moving lever 57 so as to leave the pawl 52' in set position. When lever 55 is swung forwardly, it is automatically engaged by a spring pressed catch 59' 10 to hold the pawl 52' in set position. The catch 59' is pivoted at 60 upon a bracket 61 carried by table 32, and spring 62 swings catch 59' into engagement with lever 55. An end of catch 59' projects across the upper run of belt 48 in position to be engaged by containers moved into a pocket 47 of carrier 45. Thus, as a container is moved into a pocket 47 of carrier 45 by belt 48, said container trips catch 59' so as to release lever 55 and permit actuation of rod 52 so that pawl 52' will 20 partially rotate carrier 45 and transfer this container to the support 31. In order to automatically effect this operation as soon as lever 55 is released, a weight 63 is provided on lever 57.

25 Another lever 64 is secured on an end of shaft 54 and projects rearwardly from the latter over lever 21. Lever 64 has a bracket 65 fixed thereto, and the upper end of a rod 66 extends through an aperture of this bracket 65. Bracket 65 is engaged at its under side by an abutment 67 secured on the upper end portion of rod 66, and the lower end of said rod 66 is pivoted at 68 to lever 21. An adjustable weight 69 may be provided on lever 64 to assist weight 63 in actuating the ratchet device which turns the carrier 45. The arrangement is such that when lever 55 is swung forwardly to set the ratchet device, spring 19 is allowed to elevate lever 21 and thereby disconnect gear 13 from shaft 11. Also, when lever 55 is released weights 63 and 69 actuate the ratchet device for turning carrier 45 and thereby transferring a container onto support 31. At the same time, rod 66 depresses levers 21 and 18 so as to connect gear 13 to shaft 11, whereby cam 30 may elevate support 31 to present the container to the capping head 33, and to also operate cam 41 so that the capping head is actuated to apply a closure cap to the elevated container. When the container is elevated, the ratchet device will of course be returned again to set position by actuation of lever 57.

50 In order to prevent rapid movement of parts in the actuation of carrier 45, movement of lever 64 may be controlled by a dash pot 70 which is connected to lever 64 and insures gradual downward movement of said lever 64 under the influence of weights 63 and 69.

55 Means is provided to prevent retrograde movement of carrier 45 when the ratchet device is moved to set position. For this purpose, a disk 60 71 is secured to the under side of carrier 45 and mounted to turn on shaft 46 with said carrier, said disk 71 being provided with peripheral notches 72 corresponding in number and position to the pockets 47 of said carrier. A pivoted dog 73 is arranged to engage in a notch 72 of disk 71 after each time the carrier is turned, whereby said carrier will be held against retrograde movement when the ratchet device is subsequently moved to set position. The dog 73 has a downwardly and rearwardly curved arm 74 that extends through a slot in a vertical slotted member 75 fixed to the collar 59. A spring 76 is connected to arm 74 for yieldingly swinging dog 73 to locking position. The arrangement is such

that when rod 25 is lowered, member 75 will actuate arm 74 so as to disengage dog 73 from the registered notch of plate 71. Also, when rod 25 is raised to present the container to the capping head, member 75 moves upwardly so as to allow spring 75 to swing arm 74 in a direction to engage the dog 73 in the registered notch of disk 71. This action takes place promptly upon upward movement of rod 25 so that the carrier 45 is held against retrograde rotation as lever 55 is swung forwardly to reset the ratchet device.

Means is also provided to arrest rotation of carrier 45 when the container moved thereby is registered with the support 31 and the capping head 33. This means includes a further dog 77 arranged to engage a notch 72 of disk 71 at the front of the latter as soon as a pocket 47 of carrier 45 is exactly aligned with the support 31. Dog 77 has a depending arm 78 to which is connected a spring 79 by means of which said dog 77 is moved to locking position. The arm 78 of dog 77 is operatively connected to lever 55 by means of a link 80, and this link has a lost motion connection with lever 55 through the medium of a slot 81 of link 80 and a pin 82 of lever 55 engaged in said slot. The arrangement is such that when lever 55 is swung forwardly to reset the ratchet device, dog 77 is disengaged from disk 71. Also, when lever 55 is released so to be swung rearwardly by the weights 63 and 69, spring 79 is allowed to act upon arm 78 so that dog 77 will automatically engage disk 71 as soon as the container moved by carrier 45 is registered with the support 31.

In explaining the operation of the present invention, it may be assumed that lever 55 is in its forwardly swung position with the ratchet device set for operation, catch 59' being engaged with said lever 55 as shown in the several views except Figure 5. It may also be assumed that the conveyor belt 48 has been placed in operation so that the upper run thereof travels from right to left as viewed in Figure 2, and that motor 15 has also been placed in operation. The containers to be capped are suitably deposited on conveyor belt 48, and as soon as a container enters a pocket 47 of carrier 45 at the left of the latter as viewed in Figure 2, it releases catch 59' from lever 55, whereupon weights 63 and 69 act on levers 57 and 64 to swing lever 55 rearwardly. Lever 55 actuates rod 52 so as to turn the carrier 45 through the medium of the ratchet device 50, 51 and 52', thereby transferring the container in question from belt 48 onto support 31 while the latter is in a lowered position flush with the top of table 32. The downward movement of lever 64 causes depression of levers 21 and 18 so as to operate clutch 17 and thereby connect gear 13 with shaft 11. When this takes place, the cams 31 and 41 are driven, the cam 30 causing elevation of rod 25 and support 31 so as to elevate and thereby present the container to the capping head 33 as shown in Figure 7. Cam 41 then actuates the capping head 33 so as to apply the closure cap to the elevated container. Cam 30 then lowers rod 25 and support 31 again so as to lower the capped container. During the upward movement of rod 25 and support 31, lever 57 is actuated through its connection with rod 25 and against the action of weights 63 and 69 to reset the ratchet device. At the same time, spring 19 is allowed to elevate levers 21 and 18 so as to release clutch 17 and thereby disconnect gear 13 from shaft 11. This renders the cams 30 and 41 inoperative, and the

succeeding container or belt 48 then enters the next pocket 47 of carrier 45 so as to release catch 59' and bring about the same cycle of operation again. When this happens, the capped container is moved by carrier 45 from support 31 onto belt 48 at the left hand side of the carrier as viewed in Figure 2, whereupon said belt 48 removes the capped container from the carrier and delivers it to the desired point of discharge. During this movement of the capped container from the support 31 onto belt 48, the succeeding container which has entered the pocket at the right of carrier 45 is transferred from belt 48 onto the support 31 in position to be elevated and capped. Of course, dog 77 will hold carrier 45 against retrograde movement when the ratchet device is being set, and dog 77 will enter a notch 72 of disk 71 to arrest turning of carrier 45 as soon as the succeeding container is moved onto support 31 in registration with the capping head 33. Obviously, the operation thus described will continue as long as the belt 48 is driven and containers are deposited thereon while the motor 15 is in operation.

It will thus be seen that I have provided an automatic feeding device for container capping machines, said feeding means eliminating the slow and laborious manual operation of placing containers in position to be capped, actuating clutch 17 to effect the capping operations, and removing the capped containers from the support 31. The mechanism is comparatively simple in construction and has been found extremely efficient in practical operation. While I have shown and described the preferred construction of the feeding mechanism, it will be understood that the same is susceptible of modifications and changes in details of construction such as fairly fall within the spirit and scope of the invention as claimed.

Having described the invention, what is claimed as new is:

1. A container capping machine including in combination, a capping head, a vertically reciprocable container support movable upwardly to a raised position to present the container to the capping head and movable downwardly to a lowered position to receive a container to be capped and to have a previously capped container removed therefrom, means to operate the capping head when the support is in raised position, a rotatable carrier operable to successively move containers to be capped onto the support and previously capped containers from the support when the latter is in lowered position, a conveyor to deliver containers to be capped to the carrier and to remove capped containers from the carrier, a ratchet device for intermittently operating the carrier, loss motion means operatively connecting the support to the ratchet device to set the latter in operating position when the support is raised and to leave it in such position when the support is lowered, means to automatically latch the ratchet device in set position including a catch releasable by containers as they are delivered to the carrier by said conveyor, and means to automatically operate the ratchet device upon release of the catch.

2. The construction defined in claim 1, in combination with locking means to automatically lock the carrier against rotation when the support is raised to set the ratchet device, and means to release said locking means when the support is lowered after setting the ratchet device.

3. The construction defined in claim 1, in com-

bination with spring actuated locking means to arrest rotation of the carrier when the container moved thereby is registered with the support and the capping head, and a loss motion connection between said locking means and said setting means for the ratchet device to release said locking means when said ratchet device is moved to set position.

4. A container capping machine including in combination, a capping head, a vertically reciprocable container support movable upwardly to a raised position to present a container to the capping head and movable downwardly to a lowered position to receive a container to be capped and to have a previously capped container removed therefrom, a driven shaft, means operated by said shaft to reciprocate said support, means operated by said shaft to operate the capping head when the support is in raised position, a rotatable carrier operable to successively move containers to be capped onto the support and previously capped containers from the support when the latter is in lowered position, a conveyor to deliver containers to be capped and to remove capped containers from the carrier, a ratchet device for intermittently operating the carrier, a loss motion means operatively connecting the support to the ratchet device to set the latter in operating position when the support is raised and to leave it in such position when the support is lowered, means to automatically latch the ratchet device in set position including a catch releasable by containers as they are delivered to the carrier by said conveyor, and weight operative means to automatically operate the ratchet device upon release of the catch.

5. The construction defined in claim 4, in combination with power operated driving means, a clutch operable to connect said driving means to and disconnect the same from said shaft, and means operatively connecting said clutch to the

operating means for the ratchet device, whereby the driving means is disconnected from said shaft when said support is lowered and whereby the same is connected to said shaft when the support is raised.

6. A container capping machine including in combination, a capping head, a vertically reciprocable container support movable between predetermined raised and lowered positions, means to operate the capping head when said support is in raised position, a rotatable carrier, a conveyor for successively delivering uncapped containers to and removing capped containers from said carrier, a ratchet device operable for intermittently partially rotating the carrier to successively move uncapped containers from said conveyor onto said support and capped containers from said support onto said conveyor when the support is in lowered position, a loss motion connection between said support and said ratchet device whereby the latter is set to operate the carrier when the support is raised and may remain in set position when the support is lowered, a catch to automatically latch the ratchet device in set position, said catch projecting into the path of and being releasable from the ratchet device by successive containers as they are moved to the carrier by the conveyor, and yieldable means to operate the ratchet device upon release of the catch.
